DESIGN FOR A CAN CARRIER RACK

Rudolph Cubicciotti, East Los Angeles, Calif., assignor to Union Oil Company of California, Los Angeles, Calif., a corporation of California

Application July 10, 1934, Serial No. 52,521

Term of patent 7 years

To all whom it may concern:

Be it known that I, RUDOLPH CUBICCIOTTI, a citizen of the United States, and residing at East Los Angeles, in the county of Los Angeles and State of California, have invented a new, original, and ornamental Design for a Can Carrier Rack, of which the following is a specification, reference being had to the drawing, forming part thereof.

In the drawing, Figure 1 is a perspective view of the can carrier rack, showing my design.

Figure 2 is a side elevational view on a slightly reduced scale.

Figure 3 is a rear elevational view.

I claim:

The ornamental design for a can carrier rack, substantially as shown and described.

In witness whereof I affix my signature.

RUDOLPH CUBICCIOTTI.
